CLAIM

The ornamental design for ice shaver apparatus body, as shown.

DESCRIPTION

FIG. 1 is a perspective view of an ice shaver apparatus body showing our new design;

FIG. 2 is a front elevational view thereof;

FIG. 3 is a side elevational view thereof;

FIG. 4 is a cross sectional view taken along line 4—4 in FIG. 3; and,

FIG. 5 is a cross sectional view taken along line 5—5 in FIG. 3.

The components of the ice shaver shown in broken lines in FIGS. 1-5 are shown for illustrative purposes only and forms no part of the claimed design.
